UNITED STATES PATENT OFFICE.

CARL LAURICK, OF BERLIN, GERMANY.

LOCKING DEVICE FOR THE OPERATING-CRANKS OF CASH-REGISTERS.

SPECIFICATION forming part of Letters Patent No. 707,603, dated August 26, 1902.

Application filed June 5, 1900. Serial No. 19,094. (No model.)

To all whom it may concern:

Be it known that I, CARL LAURICK, a subject of the King of Prussia, German Emperor, and a resident of Berlin, in the Kingdom of Prussia and Empire of Germany, have invented 5 certain new and useful Improvements in Devices for Locking the Operating-Cranks of Cash-Registers, of which the following is a specification.

10 The object of the invention is to provide means for preventing the turning of the operating-crank of a cash-register until the sales- man or operator has deposited within the cash- register a ticket indicating his name, num- ber, or the like.

15 The invention is illustrated in the accom- panying drawings, in which—
20 Figure 1 is a vertical longitudinal section of a portion of a cash-register casing, showing the application of the invention. Fig. 2 is a plan view of the same. Fig. 3 is a sectional detail.

In the drawings, A indicates a portion of 25 the casing of a cash-register which is deemed sufficient for illustrating the present invention. An operating crank or handle is indicated at 16, which is connected to and turns upon an operating-shaft 14. An arm 20 is carried by this shaft and in the normal position of the parts depends into the position shown in Fig. 1, where it is provided with a pin 120, which is engaged by the hooked end 30 of a locking-arm 18, pivotally secured to any fixed point within the casing. As long as this hooked arm is in engagement with the pin the crank of the register is locked against movement. In order to disengage the arm 18 from the pin, I provide a rocking lever 129, carrying at its rear end a pawl 130, hav- 35 ing a hooked portion engaging the hooked end of the arm 18. The forward end of the lever 129 is designed to be operated by the slide mechanism hereinafter described.

A slide 23 is suitably guided in the walls 45 of the casing and has in its upper surface a recess to receive a suitable ticket (indicated at 21) which may be inserted through an opening 22 in the projecting portion of the casing. This slide tends to move toward the rear by the tension of a spring in the manner hereinafter described. A retaining-lever 50 121 is pivoted to a lug or projection 121^a on

the under part of the slide, and the lever is provided on its front end with a hook or catch 55 designed to engage with the edge of the cas- ing to thus lock the slide against rearward movement. The catch is held in engagement with the casing by a spring 133, and the pro- jecting portion 133^a serves as a handle for the depression of the front end of the lever. In 60 order to hold the lever 121 against movement except when the ticket has been inserted, I provide a transverse rock-shaft 29, which has a plurality of depending fingers 30 extending down into the path of the ticket and also other 65 fingers or projections 31, designed to engage the rear end of the lever 121, as shown in Fig. 1. When, however, the ticket 21 is inserted and shoved rearwardly, the impact of the ticket 70 against the fingers 30 causes the projections 31 to be moved out of contact with the rear end of the lever 121, which may then be depressed to release the slide. A supplemental slide 125 is suitably guided in the casing and is under the tension of a spring 122, connected to a pin 75 132 and tending to draw said slide 125 toward the rear. A pin 134, carried by the slide 125, engages the front side of a stop 124 when the slide 125 moves rearwardly, and thus tends to carry the slide 23 back with it. 80 The slide 125 has a projection 128, which en- gages the forward end of the lever 129 when the slide nears the limit of its backward movement, and thus releases the pin 120 from the arm 18 in the manner hereinbefore de- 85 scribed. In order that the slide 23 may be restored to initial position, the cash-drawer (not shown) may be caused to engage the pin 132 when it is drawn out, and thus carry the slide 125 with it. A pawl 126 is pivotally 90 connected to the slide 125 and has one edge adapted to slide upon the lower edge 127 of the guide, thus holding its upper edge or nose in contact with the rear side of the stop 124 until the slide 23 has been drawn forward 95 sufficiently to allow the catch on the lever 121 to engage the edge of the casing. When this point is reached, the lower edge of the pawl 126 reaches the cut-away portion 127^a, which permits the pawl to rock backward, as 100 indicated in dotted lines, to clear the projec- tion 124 and the cash-drawer to continue its outward movement without affecting the slide 23. On the reverse movement of the cash-

drawer the pawl will rock in the opposite direction and the slide 125 moves backward under the tension of the spring until the lower edge of the pawl engages the edge 127 of the 5 guide and the pin 134 comes in contact with the projection 124. The ticket which is carried rearwardly by the slide 123 is held against being carried forwardly again by a spring-pawl 135 and is dropped into a suitable 10 portion of the register-casing. (Not shown.) A glass 123 permits of the inspection of the ticket when it has been carried rearwardly by the slide.

From the foregoing description the operation 15 of the device will be clear, but may be briefly stated as follows: The crank 16 of the cash-register is normally held against movement, as indicated in Fig. 1. The salesman who desires to operate the cash-register inserts 20 a ticket through the opening 22 and pushes it rearwardly until it swings the projections 31 out of engagement with the lever 121. The operator then depresses the end 133^a, which releases the slide and allows it 25 to be drawn rearwardly under the action of the spring 122, slides 23 and 125 moving rearwardly together. As soon as the slide 125 nears the limit of its backward movement the projection 128 contacts with the forward 30 end of the arm 129 and raises the pawl 130, and with it the arm 18, thus freeing the arm 20 and allowing the cash-register handle to be operated. The cash-register may now be operated in the usual manner. In order to 35 prevent a double rotation of the handle without the slides having been moved forward by the opening of the cash-drawer, a pawl 131 is pivoted to the arm 20, and which as the arm 20 nears its initial movement engages the 40 pawl 130 and rocks it to disengage it from the end of the arm 18, allowing the end of said arm to drop into engagement with the pin 120.

Having now described my invention, what 45 I claim as new, and desire to secure by Letters Patent, is—

1. The combination with the operating-crank of a cash-register, of a locking device for holding the same against movement, a 50 slide for releasing said locking device, a spring tending to retract said slide, means for holding the slide normally advanced, and check-controlled means for releasing said holding means, substantially as described.

2. The combination with the operating-crank of a cash-register, of a locking device for holding the same against movement, a slide adapted to release said locking device on its rearward movement, a spring for drawing 55 said slide backward, a catch-lever for holding said slide advanced against the tension of the spring and check-controlled means for holding said catch-lever normally locked, substantially as described.

3. The combination with the operating-crank of a cash-register, of a locking device for holding the same against movement, a

slide adapted to release said locking device on its rearward movement, a spring for drawing said slide backward, a catch-lever for holding said slide advanced against the tension of the spring, a locking-finger engaging said catch-lever to hold it normally against movement a check-receiving space in said slide, and a finger projecting into the path of the check and operatively connected with said locking-finger, substantially as described. 70

4. The combination with the operating-crank of a cash-register, of a locking device therefor, a slide adapted to release said locking device, a spring tending to retract said slide, a catch-lever pivoted to the slide and engaging a rigid portion of the casing to hold the slide against movement, the rear end of said catch-lever projecting through an opening in the slide, a rock-shaft above the slide having a locking-finger engaging the rear end of said lever, said slide having a check-receiving space or guide, and a finger carried by said rock-shaft and projecting into the 80 path of the check, substantially as described. 85

5. In combination with the operating-crank of a cash-register, of a locking device therefor, a slide adapted to release said locking device on its backward movement, a spring for 90 retracting said slide, a catch-lever pivoted to the slide and adapted to project through an opening in the casing and automatically engage the edge thereof at the limit of its forward movement to prevent backward movement of the slide, the rear end of said lever projecting into an opening in the slide, a rock-shaft having a locking-arm engaging said rear end, said slide having a check-receiving space or guide, an arm or finger on 95 the shaft projecting into the path of the check, and a hook for engaging the check when the slide is retracted whereby said check is removed from the slide on the forward movement of the latter, substantially 100 as described.

6. The combination with the operating-crank of a cash-register, of a pivoted hook for holding said arm against movement, an oscillating lever adapted to disengage said hook, 115 a slide adapted to oscillate said lever on the backward movement of the slide, a spring tending to retract said slide, a catch-lever normally locked against movement for holding said slide advanced against the tension of the 120 spring, and check-controlling means for unlocking said lever, substantially as described.

7. The combination with the operating crank-shaft of a cash-register, of an arm carried by said shaft, having a pin, a pivoted 125 hook engaging said pin, an oscillating lever, a pawl on the rear end thereof engaging said hook, check-controlled slide adapted to operate said oscillating lever to disengage the hook from the pin, and a hook-shaped pawl on the 130 arm adapted, on one rotation of the arm to disengage the pawl from the hook, substantially as described.

8. The combination with the operating-

crank of a cash-register, of a device for locking the same against movement, an oscillating lever adapted to release said locking device, a slide having a check-receiving space 5 or guide, means released by the insertion of a check for holding said slide normally locked, a supplemental slide having a projection for operating said oscillating lever, a retracting-spring connected to said supplemental slide, 10 a projection on the supplemental slide adapted to engage a projection on the check-carrying slide to move said check-carrying slide rearwardly, a pawl carried by the supplemental slide adapted to engage the rear face of 15 the projection whereby forward movement of the supplemental slide secures forward movement of the main slide, and means whereby said pawl is released at a determined point to permit the supplemental slide to move forward 20 without affecting the main slide, substantially as described.

9. The combination with the operating-crank of a cash-register, of a device for locking the same against movement, an oscillating lever adapted to release said locking device, a slide having a check-receiving space 25

or guide, means released by the insertion of a check for holding said slide normally locked, a supplemental slide having a projection for operating said oscillating lever, a retracting-spring connected to said supplemental slide, 30 a projection on the supplemental slide adapted to engage a projection on the check-carrying slide to move said check-carrying slide rearwardly, a pawl carried by the supplemental slide adapted to engage the rear face of the projection whereby forward movement of the supplemental slide secures forward movement of the main slide, said pawl having a straight lower edge, a guide against which the 35 said straight lower edge bears during the rear portion of the movement of said slide, said guide having a cut-away portion to permit rocking of the pawl to disengage it from the projection on the main slide, substantially as 40 described.

In witness whereof I have hereunto set my hand in presence of two witnesses.

CARL LAURICK.
